PICKPROOF LOCK CONSTRUCTION

Sigurd Brantingson, Palisades Park, N. J., assignor to Francis Keil & Son, Inc., a corporation of New York

Application November 3, 1938, Serial No. 238,515

11 Claims. (Cl. 70—364)

This invention relates to lock construction and more particularly to a lock construction of the pin tumbler type.

One of the objects of this invention is to provide a lock construction that will effectively resist picking and which in construction will be free from costly complications. Another object is to provide a pickproof lock construction of the pin tumbler type which will be inexpensive to manufacture and which so far as manufacture is concerned may be easily made to follow routine manufacturing processes as employed in the present-day low cost type of cylinder or pin tumbler lock manufacture. Another object is to provide a pickproof lock construction that will be inexpensive to manufacture, that makes it possible to avoid peculiarly shaped and expensive parts, and that will make it possible to employ existing methods of assembly. Another object is to provide a simple and dependable pin tumbler lock construction capable of utilizing simple and inexpensive forms of pins or pin tumblers and yet constructed and operating to resist effectively attempts to pick it.

Another object is to achieve in a lock of the pin tumbler type genuine proof against picking without having to import into the construction complicated modifications of structure or cost-increasing additional parts and thus to make available to the public a low cost but genuinely pickproof lock construction. Many attempts have heretofore been made to produce a pin tumbler lock construction incapable of being picked. In some of these attempts, so-called "mushroom" or headed upper or driver pins have been employed sometimes throughout the lock construction and sometimes in combination with straight or cylindrical or with cylindrical but end-tapered driver or upper tumbler pins and, in fact, structures according to such prior attempts are today on the market, but all of them can be actually picked and they simply increase to a small extent the time and difficulty in picking the lock as against the time and difficulty involved in picking the ordinary lock in which all of the pins are cylindrical.

Other attempts have been made by utilizing one or more mushroom or headed driver or upper tumbler pins and even also one or more mushroom or headed pins in the key plug, in coaction with added moving parts in the form of disks, slides, sleeves, or the like, or other additional part or parts intended to partake of movement relative to the casing and the key plug and to the necks or heads of the mushroom pins, in the endeavor

to achieve proof against picking, but in such instances, aside from other shortcomings, the structural complications are so great that either cost of production and hence cost to the consumer is prohibitively high or there results such unreliability of normal or other action as to forestall commercial success.

Other attempts disclosed in the prior art include the use of a long pin in the key plug, usually at the front end of the latter, dimensioned as 10 to length so that the insertion in the key slot of a picking tool lifts the pin into the tumbler recess or bore contained in the lock casing, the intention being that thereby such relative displacement, as by applying a torsional or twisting force 15 on the key plug, between the casing and key plug, as is necessary to catch or hold other tumbler pins, is prevented; but such structures of the prior art can be easily picked and the latter characteristic doubtless accounts for the fact that, 20 though such structures have been long disclosed or known in the prior art, they are not on the market.

One of the dominant aims of this invention is to avoid and overcome such commercially fatal 25 and other deficiencies and disadvantages as those pointed out above, and to produce a low cost, dependable, secure and durable lock construction that effectively precludes picking. Other objects will be in part obvious or in part pointed out 30 hereinafter.

The invention accordingly consists in the features of construction, combinations of elements, and arrangements of parts as will be exemplified in the structure to be hereinafter described and 35 the scope of the application of which will be indicated in the following claims.

In the accompanying drawing in which is shown by way of illustration one of the various possible mechanical embodiments of my invention, 40

Figure 1 is a central vertical longitudinal sectional view through the lock construction;

Figure 2 is a transverse sectional view as seen along the line 2—2 of Figure 1;

Figure 3 is a transverse sectional view as seen 45 along the line 3—3 of Figure 1;

Figure 4 is a fragmentary side elevation of the key plug, and

Figure 5 is a sectional view like that of Figure 1 but on a smaller scale and fragmentary, showing 50 the relationship of the parts with a proper key inserted into the lock construction.

Similar reference characters refer to similar parts throughout the several views in the drawing.

Referring first to Figure 1, I have there shown 55

at 10 a lock casing having a lower casing portion 11 preferably cylindrical (see Figures 2 and 3) and bored out, preferably also cylindrically, as at 12, for movably receiving therein a key plug 13, preferably cylindrical, and neatly fitted into the bore 12 to partake of movement relative thereto. The key plug and the casing are provided each with bores or recesses for the reception of upper and lower tumbler pins, all in the preferred manner as later described, the casing 10 having an upper extension or casing portion 14 in which the bores CB, preferably cylindrical, are formed, the bores being preferably cylindrical and being preferably drilled with their axes preferably parallel and falling in a plane that preferably passes through the axis of the bore 12 and hence also through the axis of the key plug 13. In the key plug 13 is a key slot 15 which may take any suitable or appropriate form, illustratively like that shown in Figures 2 and 3, being preferably of generally rectangular cross-section but longitudinally ribbed, thus to adapt it to take a flat key suitably grooved longitudinally to interfit with the ribs of the key slot. Thus, the upper portion may have a plurality of V-shaped ribs R arranged, for example, two on the left-hand side and one on the right-hand side and the intermediate or rest of the rectangular cross-section may have two spaced ribs 17 and 23 on the right-hand side and an intermediate rib 16 on the left-hand side. Rib 17 may have a substantially horizontal under face and rib 16 may have a substantially horizontal upper face, and these two faces are vertically displaced. In the key plug 13 I provide pin tumbler bores PB preferably with their axes parallel and coincident generally with the central vertical plane of the key slot 15, the latter being preferably aligned along the central vertical plane of the key plug 13 with the latter positioned in its normal or locked position.

The key plug bores PB are preferably formed by drilling and may be of any suitable number, illustratively six, and of any suitable length or lengths. The bores PB may be and preferably are of the same axial length, thus avoiding complications in manufacture. As better appears from Figures 2 and 3, the bores are drilled so as to intersect the upper ribs R and they preferably

But for achieving freedom from binding and ease of turning movement, it is preferable to allow for a slight play in an axial direction, particularly also because of necessary tolerances in manufacture and assembly. Accordingly, the flange 18 and ring 20 may permit a relative axial movement between casing and key plug of several thousandths of an inch, for example three or four thousandths.

In the preferred construction, the diameters of the casing bores CB and key plug bores PB are the same and preferably uniform throughout; illustratively, they may be of a diameter of 0.123 inch.

In the casing tumbler bores CB I provide casting tumblers preferably in the form of cylindrical pins and preferably of the same length but each of a diameter preferably materially less than the bore in which it is received. Thus, where the bores CB are all of the same diameter and of 0.123 inch by way of the above illustration, these casing tumbler pins E¹, E², E³, E⁴, E⁵ and E⁶ are preferably of the same diameter and illustratively of 0.115 inch. This difference in the diameters includes a factor adequate to compensate for the above-mentioned end play or relative axial play between key plug and casing and insures that the pins E², E³, E⁴, E⁵, E⁶, under the action of the springs S are entered into the key plug bores PB, even though this end play results in a slight misalignment between key plug bores and casing bores. The casing bores CB may be closed off as by a plate 21.

Coating with the tumbler pins E², E³, E⁴, E⁵ and E⁶ are key plug tumbler pins K², K³, K⁴, K⁵, K⁶, respectively; these may be of differing lengths according to the particular coding selected for the lock and for the corresponding key and each preferably matches the diameter of its coating casing tumbler pin. In the illustrative case, these key plug pins K² to K⁶ are therefore preferably 0.115 inch in diameter. Here again, allowance is included in the dimensional difference for possible end play between key plug and casing and thus the entry of the pins K² to K⁶ into the casing bores CB, under the action of a key, is assured even though the respective upper and lower bores might be slightly out of line axially. These tumbler pins bottom in their

stantially tangent to the uppermost end of the cylindrical wall of the bore PB, whence it extends downwardly and toward the center line of the bore PB, intersecting the bottom of the plug bore PB along the diameter of the latter and extending sufficiently downwardly, as viewed in Figures 4 and 2, so as substantially to terminate at or preferably slightly below the upper face of the rib 16, thus also intersecting the key slot 15 as well as the bore PB of pin K¹.

Plate P is of a thickness on the order of several thousandths less than the width of the slot 22, so that it may freely move in the slot and where the slot 22 has an arcuate bottom 24, the bottom edge 25 of plate P is likewise and preferably arcuate, so that it may snugly bottom in the slot 22 even though slightly displaced to the left or right of the center line; the plate P is of a length, as viewed in Figure 2, such that its arcuate bottom edge 25 is somewhat less than the arcuate length of the bottom 24 of the slot 22, and when bottomed in the latter it closes off the key slot portion 15^a that is to the left of the rib 17 and it also closes off that portion of the key slot that is above the horizontal plane through the upper face of the rib 16, the matching curvatures of slot bottom 24 and bottom edge 25 of the plate P insure that this closing off of these portions of the key slot dependably take place even though the plate P is shifted somewhat to the left or right of exact coincidence of center lines of plate and key plug.

The upper edge of plate P is cut out to form a seat for the lower end of pin K¹ and this seat 35 may have a preferably straight line bottom edge 26 of a length equal to or slightly greater than the diameter of pin K¹, bounded on each side by upwardly and outwardly inclined edges 27, 27.

In assembly, plate P is first slipped into the 40 slot 22, thus bringing its seat-like edge 26 cross-wise of the bore PB, whence the pin K¹ is dropped in its bore, its lower end being dependably guided into contact with the seat 26 by the outwardly diverging guiding edges 27, 27, the reaction of 45 the pin K¹ on the latter edges being such as to nicely center the plate P.

With the plate P bottoming in the slot 22 and the pin K¹ resting in its seat on the plate P the 50 length of pin K¹ is such that its upper end is flush with the outer cylindrical surface of the key plug (see Figure 1) and it thus coincides with the line or plane of junction between key plug and casing bore.

In diameter, pin K¹ is preferably larger than 55 that of the illustrative equal-diametered pins K² to K⁶ and preferably is only sufficiently smaller in diameter than the diameter of its own two bores PB and CB, as is necessary to compensate for the above-mentioned end or axial play between key plug and casing. With the above 60 illustrative dimensions of other parts, this tumbler pin K¹ is illustratively of a diameter of 0.118 inch. This difference between its own diameter and that of the casing bore CB with which it is to 65 coact insures that it dependably enters the latter in spite of the above-described end play. If it were possible at low cost to eliminate such end play completely, the above set forth illustrative dimensions could be correspondingly revised to 70 avoid compensating for end play but the difference in diameters between tumbler pin K¹ and the illustratively equally-diametered tumbler pins K² to K⁶ would be retained, for a purpose presently to be described.

75 In normal or locked position of the parts they

appear as is shown in Figure 1. The junction between pins E¹ and K¹ coincides with the junction between key plug and casing bore so that neither of these two pins takes part in preventing relative movement between key plug and casing. But depending upon the coding of the key and other factors, the junctions between the remaining pairs of upper and lower tumbler pins are displaced from the junction between key plug and casing bore, being illustratively displaced 10 downwardly therefrom in varying degrees, and thus the construction is held in locked position.

In such locked position, the construction cannot be picked, as explained below, and to unlock it, a flat key Y (Figure 5) having longitudinal 15 lateral grooves to mate with the ribs R, 17, 16 and 23, is inserted into the key slot 15 in the usual way, the key having a cross-section to match the cross-section of the key slot 15; its upper edge is so shaped that the junctions between the pairs of tumbler pins E²—K², E³—K³, etc., are brought and held in coincidence with the junction between key plug and casing bore, as is indicated in Figure 5 with respect to the tumbler pins E²—K², while the junction between 25 pins E¹ and K¹ is maintained in similar coincidence, the key Y when brought to rest having a notch therein, corresponding to the location of the pin K¹ or of plate P, of such depth as is clearly indicated in Figure 5 that the plate bottoms in 30 its slot 22 and the upper end of pin K¹ is coincident with the above-mentioned junction. Thus, with such a key the lock may be unlocked.

The lower edge 25 of plate P is in transverse cross-section rounded off, as indicated in Figure 1, thus more smoothly to coact with the notched key edge. As the forward notches of the key lift up the plate P, pin K¹ is also lifted up but lateral displacement of the plate P is prevented due to the action of the spring S and the 40 projection of the lower end of pin K¹ between the side walls 27, 27 of the seat.

Without the proper key, however, it has been found impossible to bring about an actuation of the lock and a better understanding of this result can be had by considering briefly such prior art constructions as heretofore mentioned which propose to employ a tumbler pin in the key plug, in the first bore thereof, and of a length equal to the key plug tumbler bore itself. The procedure in picking such a prior construction, and it is a matter of only a few minutes, is first to employ a suitable picking tool which is inserted into the key slot, thus raising the front tumbler pin and hence projecting its upper end into the 55 tumbler bore of the casing; it can be held in such upwardly projected position by exerting a torsional strain on the key plug.

If there is no play or difference in pin and bore diameters, the picking tool may then be employed 60 to force successively the other tumbler pins upwardly to bring their junctions in coincidence between the key plug and casing bore junction, for the upwardly projected guard pin prevents any such relative displacement between upper 65 and lower pin bores as would preclude pushing the key plug pins upwardly to move the upper tumbler pins into their respective casing bores. If there is uniform play throughout, the same action results.

In each instance the tumbler pins to the rear of the guard pin can be pushed upwardly to the right respective positions and when the picking tool is removed, while still maintaining through other means the torsional strain on the key plug, 75

there remains only the last step which is gradually to pull the front or guard pin downwardly to the desired extent. This may be done by using a sharp pointed instrument and by its point forcing the guard pin down. When that is done, the key plug can be turned.

In other prior art attempts, the construction is such as to require an additional or special configuration of the key and usually, also, such structural complications of key plug and tumbler pins and arrangements that cost is prohibitive, the resultant construction impracticable, or other and more controlling deficiencies or weaknesses are brought about.

With the construction of my invention, however, such lack of security and disadvantages inherent in prior proposed constructions are not present. Because of the manufacturing tolerance or axial end play of several thousandths of an inch between the key plug and the casing, the diameter of the front or long pin K^1 is illustratively 0.118 inch where the diameter of the bores PB and CB with which this pin coacts is 0.123 inch. Thus, for all normal operations on or of the lock construction, proper entry of the pin K^1 into the upper or casing bore CB is assured in spite of such axial play between key plug and casing. Were it not for such axial play, this pin K^1 would far more closely match the diameter of its coating bores PB and CB. If, with the construction above described, it should become possible, through the front end of the key slot 15, to manipulate the plate P or the pin K^1 , the only possible movement that can be transmitted to the latter is an upward movement and that necessarily results in projecting the upper end of pin K^1 into the bore CB, with results later explained.

But it becomes exceedingly difficult to effect such a manipulation of the pin K^1 . In the first place, the plate P and the pin K^1 are preferably not joined together mechanically so that the operator has two independently movable pieces to contend with. For example, if he is able with the picking tool to lift the pin K^1 directly by operating through an upper portion of the key slot, the plate P remains bottomed in the slot 22 and continues to form a barrier to access to those tumbler pins that are to the rear of the pin K^1 . If the plate P is displaced upwardly by a picking tool, it moves the pin K^1 upwardly into locking position and in either case, though pin K^1 may be held upwardly displaced by a torsional strain imposed upon the key plug, the same holding action is ineffective to hold the plate P displaced upwardly and the latter drops down to bottom in the slot 22. In such position it blocks off that portion of the key slot in line with the lower ends of the tumbler pins K^2 to K^6 and particularly that portion of the key slot above the rib 16 and below the rib 17 (see Figures 2 and 3).

Assuming, however, that it were possible to achieve an upward projection of pin K^1 and that thereafter a strain, such as a torsional strain, is imposed upon the key plug 13 so as to misalign the plug bores PB with respect to their respective casing bores, such misalignment takes place to an extent permitted by whatever differential exists between the diameter of the pin K^1 and the diameter of its coating bores PB and CB; in Figure 2 I have shown the pin K^1 thus raised and have indicated a slight rotary displacement of the key plug 13 relative to the casing, such displacement being due to the presence of the dimensional differential between the diameter of pin K^1 and the diameter of its bores PB and CB

necessitated by the axial end play between key plug and casing caused by the action of the parts 18 and 20, as above described. If no such axial play were present, such a dimensional differential need not be present and Figure 2 would appear without appreciable or substantial rotary displacement of the key plug relative to the casing. The same misalignment is necessarily brought about as to each remaining pair of plug bores and casing bores PB and CB, respectively, that being permitted and adequately provided for because the diameters of the pins in the remaining bores, illustratively being of a diameter of 0.115 inch, are less than the diameter of the pin K^1 , the latter being illustratively 0.118 inch.

In the illustrative dimensional embodiment, therefore, no restriction of what might be termed the throat or passageway at the junctions between the plug bores and casing bores can take place beyond the diameter of 0.118 inch, as determined by the guard pin K^1 . That restriction or throat is, however, insufficient to prevent the free passage therethrough of any of the remaining tumbler pins so that it becomes impossible, having once raised the guard pin K^1 , as above assumed, thereafter to cause any of the pins E^2 to E^6 or K^2 to K^6 to be frictionally held or otherwise gripped or gaged as to the location of the junction between upper and lower pins, nor is it possible to cause an upper tumbler pin E^2 to E^6 to be caught on any possible ledge or edge of the key plug, for the spring pressure coupled with the minimum throat dimension of 0.118 inch dependably insures that the still smaller-dialed pin, namely, of 0.115 inch, freely moves downwardly through the restriction or throat in question. The physical relationship involved in these actions is shown in Figure 3.

The tumbler pin K^1 will thus be seen to act not merely to block relative movement between key plug and casing by being projected upwardly by the inserted picking tool, but it is made, in coaction with the dimensional differentials, above illustratively set forth, to so prepare any subsequently possible restriction of the throat or passageway at the junction between upper and lower tumbler bores as to make any subsequent manipulation of key plug and other tumbler pins effective to catch or hold or position all of the remaining tumbler pins at the critical unlock-positions. The simplest mechanical embodiment for carrying out the just stated coactions is that shown in the drawing and above described in that it is possible to have uniform diameters and straight-line alignment of tumbler pin bores and only two different diameters of tumbler pins; also, it is possible to use straight cylindrical pins throughout, of which all may be of the same or smaller dimension, and the one pin, pin K^1 , alone can be of the larger diameter. In connection with the above-described actions, it should be noted that though the slot 22 (Figures 1 and 4) intersects the plug bore PB of the pin K^1 , it does so in a manner that does not increase any existing or possible play between the pin and its bore, and in the illustrative embodiment that is achieved by the angular relationship of the slot to the axis of the bore, as shown in Figures 1 and 4 and described above. This angular relationship insures that, throughout the axial length of the pin K^1 , the effective bearing surface provided by its bore PB is, as viewed in the direction of the axis of the bore, continuously cylindrical; were the axis of the slot 22 to be coincident with the axis of the 75

bore PB, the cylindrical surface of the bore would be interrupted on both sides and throughout its length, thus giving rise to increased play when the general positions of the parts as shown in Figure 2 are to be achieved, and such action might permit such a throat restriction as would let the smaller diametered pins be caught rather than to be freely passed therethrough, as in Figure 3.

10 Also, though I have shown the pin K¹ positioned in the first tumbler recess of the key plug, it may be given a different position in the total series of tumbler pins but preferably always such a position that one or more other tumbler pins are to the rear of it.

15 With the above-described attempt to pick this construction failing, let it be assumed that attempt is now directed along different lines, namely, to avoid upward projection of the pin K¹ and to attempt manipulation of the pins to the rear of pin K¹. In such case, the plate P must be allowed to remain in its lowermost position, namely, with its lower edge 25 coinciding with the bottom 24 of the slot 22, thus closing off those portions of the key slot above the rib 16 and below the rib 17, making access to the rear pins impossible or impracticable; I have found in practice that the tortuous cross-section of the key slot above the lower edge of the plate P when it is bottomed in its slot, as just mentioned, makes it impossible to get to the rear pins and to manipulate them in the effort to get their junctions alined with the junction between key plug and casing bore. Invariably upward displacement of the plate P results if the rear pins are to be reached with any picking tool and if they are so reached and displaced, the above described coactions and results take place. Should the effort be repeated to reach a rear pin without displacing the plate P upwardly, it is to be noted that such effort is always accompanied by application of torsion or twist to the key plug 13 and due to the dimensional differentials above-described, any one of the rear pins, such as pin E³, for example, permits a restriction or throat reduction throughout the construction to 0.115 inch, that being the diameter of pin E³, and in such case the restriction is too small to permit upward projection of pin K¹ whose diameter is 0.118 inch, with the result that plate P becomes positively locked in the bottom of the slot 22, thus positively blocking off those very portions of the key slot through which access to the rear pins has to be gained.

55 The plate P can be inexpensively stamped out of flat stock and if desired it may be made of a metal having or treated to have sufficient hardness to resist drilling. Assembly of pin K¹ and plate P with the key plug is simple and inexpensive and the upwardly tapered or widening seat 27-26-27 permits independent movements of pin K¹ and plate P and also conjoined movements thereof but without causing the force exerted on one to effect a binding action between the other and its guideway. Also, the plate P may be tilted as might happen if actuated by a picking tool applied to it at a point displaced from the central vertical axis, as viewed in Figure 2, in which case the plate P acts like a lever to lift the pin K¹, fulcruming upon the bottom 24 of the slot at one or the other of the lower lateral corners of the plate.

70 Thus, it will be seen that there has been provided in this invention a lock construction in

which the various objects hereinbefore set forth, together with many thoroughly practical advantages, are successfully achieved. The construction will be seen to be simple, inexpensive to manufacture, and is dependably pickproof, and, moreover, it can be manufactured at low cost and made available to the consumer at a price substantially the same as or comparable to that of the ordinary or usual type of pin tumbler locks.

75 As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

10 I claim:

1. A lock construction comprising a casing and a key plug, said key plug having a key slot therein and a plurality of tumbler bores intersecting said key slot, said casing having a plurality of tumbler bores respectively alinable with said first-mentioned tumbler bores, the axes of said bores when said key plug is in position to have its bores alined respectively with the casing bores 25 falling in a common plane, said key plug having a slot extending in a direction crosswise of the plug axis and intersecting said key slot, said slot intersecting a bore in said key plug other than the rearmost one, a plate normally bottoming in 30 said slot and closing off at least a portion of said key slot, a tumbler pin in said intersected bore and extending upwardly beyond the upper edge of said plate, the lower edge of said plate being exposed in said bore below the lower edge of said 35 tumbler pin, thereby to be engageable by a key or implement inserted in said key slot, said plate and said pin being of such relative lengths that, when said plate bottoms in its slot, the upper end of said pin is coincident with the junction between key plug and casing, and tumbler pins in the rest of said bores including spring pressed 40 tumbler pins in the casing bores.

2. A lock construction comprising a casing and a key plug, said key plug having a key slot therein and a plurality of tumbler bores intersecting said key slot, said casing having a plurality of tumbler bores respectively alinable with said first-mentioned tumbler bores, the axes of said bores when said key plug is in position to have its 45 bores alined respectively with the casing bores falling in a common plane, said key plug having a slot extending in a direction crosswise of the plug axis and intersecting said key slot, said slot intersecting a bore in said key plug other than 50 the rearmost one, a plate normally bottoming in said slot and closing off at least a portion of said key slot, a tumbler pin in said intersected bore and extending upwardly beyond the upper edge of said plate, the lower edge of said plate 55 being exposed in said bore below the lower edge of said tumbler pin, thereby to be engageable by a key or implement inserted in said key slot, said plate and said pin being of such relative lengths that, when said plate bottoms in its slot, the upper end of said pin is coincident with the junction between key plug and casing, said tumbler pin having a diameter relative to the alinable bores in which it operates such that, when it is bridged across said junction, substantially no 60 displacement, or only a slight displacement, between adjacent ends of casing and key plug bores can take place, and tumbler pins in the rest of said bores including spring pressed tumbler pins 65 in the casing bores having such smaller diameters 70 in the casing bores having such smaller diameters 75

relative to their respective bores that they always freely pass across the junction between casing and key plug when said first-mentioned pin is bridged across said junction and a displacement to the extent permitted by said pin is effective.

5 3. A lock construction as claimed in claim 1 in which said plate has in its upper edge a seat for the lower end of the tumbler pin, said seat comprising a cutout in the upper edge of said plate for receiving therein the lower end of said pin.

10 4. A lock construction as claimed in claim 1 in which said plate has in its upper edge a seat for the lower end of the tumbler pin, said seat comprising a three-sided cutout in the upper edge of said plate, the bottom side being dimensioned commensurately with the lower end of the pin and the remaining two sides being inclined upwardly and away from the pin.

15 5. A lock construction as claimed in claim 1 in which the bore that is intersected by said slot is cylindrical and the slot intersects the bore at an angle to the axis of the bore.

20 6. A lock construction as claimed in claim 1 in which the portion of the key slot normally blocked off by said plate comprises a part to one side of a rib extending longitudinally of the key slot and another part extending below said rib, the remaining tumbler pins in the key plug bores 25 terminating at or above the lower edge face of said rib.

25 7. A lock construction as claimed in claim 1 in which the bottom of the slot is arcuate in substantially upwardly concave form and the bottom edge of the plate is commensurately arcuate but in substantially downwardly convex form, whereby said plate substantially self-centers itself with respect to the key slot.

30 8. A construction as claimed in claim 1 in which said slot is open at side portions of the key plug, said plate being of substantial dimension in a direction crosswise of the plug axis, whereby the walls of the casing bore that receives the key plug are effective to prevent substantial lateral displacement of said plate.

35 9. A lock construction comprising a casing and a key plug, said key plug having a key slot therein and a plurality of tumbler bores intersecting said key slot, said casing having a plurality of tumbler bores respectively alinable with said first-mentioned tumbler bores, means co-acting between said key plug and said casing for holding said key plug against axial movement while permitting rotary movement thereof relative to said casing, said holding means permitting a slight axial play between said key plug and casing, tumbler pins in said casing bores and tumbler pins in said key plug bores, one of said key plug tumbler pins other than the rearmost one 40 having a length such that in normal position of the lock parts its upper end is coincident between the junction between the key plug and casing,

45 said one tumbler pin having a diameter slightly less than the bores within which it acts sufficient to let it enter into its casing bore in spite of said axial end play permitted by said holding means, and all of the remaining tumbler pins having 50 diameters less than the respective bores within which they operate to an extent sufficient always to pass through the restriction effected at the junction between the key plug and the casing permitted when said one tumbler pin is projected 55 upwardly across said junction and the key plug is displaced relative to the casing to the extent permitted by said one tumbler pin, and springs 60 acting upon the tumblers in said casing tumbler bores to press them always through any restriction at said junction as aforesaid.

65 10. A construction as claimed in claim 9 in which said key slot is generally of rectangular cross-section to take a flat key but has in its walls a plurality of inwardly projecting longitudinally 20 extending ribs received in corresponding grooves in the sides of said key, two of said ribs being vertically displaced, the key plug having a recess intersecting said key way and the bore containing said one tumbler pin, a plate in said recess 25 terminating at or just below the upper face of the lower of said two ribs and bridging those portions of the key slot below and laterally of the upper of said two ribs, said one tumbler pin engaging the upper portion of said plate, and the 30 bores of all such tumbler pins in the key plug as are to the rear of said one tumbler pin terminating substantially at or above the lower face of the upper of said two ribs.

70 11. A lock construction comprising a casing 35 and a key plug, said key plug having a key slot therein and a plurality of tumbler bores intersecting said key slot, said casing having a plurality of tumbler bores respectively alinable with said first-mentioned tumbler bores, the axes of 40 said bores when said key plug is in position to have its bores alined respectively with the casing bores falling in a common plane, a tumbler pin in one of said key plug bores other than the rearmost and being of a length such that in normal position of the lock parts its upper end is coincident with the junction between key plug and casing, and having a diameter relative to the alinable bores in which it operates such that, when it is bridged across said junction, substantially no displacement, or only a slight displacement 45 between adjacent ends of casing and key plug bores can take place, and tumbler pins in the rest of said bores including spring pressed tumbler pins in the casing bores having such 50 smaller diameters relative to their respective bores that they always freely pass across the junction between casing and key plug when said one pin is bridged across said junction and a displacement to the extent permitted by said one 55 pin is effective.

SIGURD BRANTINGSON.
